BALLAST CLEANING APPARATUS

Charles A. Gill, Reading, Pa.

Application December 16, 1936, Serial No. 116,174

7 Claims. (Cl. 262—2)

The invention relates to ballast cleaning and has as an object the provision of a self-propelled plant to remove ballast from the right of way, screen it, return the cleaned stone to the right of way, and to load the dirt screened out upon a railway car.

It is a further object of the invention to provide a device of the class described having the excavating apparatus adjustable not only for height but for overall width in such a manner that it may be retracted from tie-end clearing to a position in which it will not extend beyond the outline of the usual railway car.

It is a further object of the invention to provide an excavator and power plant for driving of the same upon a platform movable for the purpose above referred to, and a drive for the car upon which the device is mounted operable from the said movable power plant.

Further objects of the invention will appear from the following description when read in connection with the accompanying drawings showing an illustrative embodiment of the invention, and wherein:

Figure 1 is a perspective view of the excavating and drive mechanism of the invention;

Fig. 2 is a transverse vertical section on line 2—2 of Figure 1;

Fig. 3 is a plan view of the screen end of the car upon an enlarged scale;

Fig. 4 is a vertical section on broken line 4—4 of Fig. 3;

Fig. 5 is a detail vertical section on line 5—5 of Fig. 3;

Fig. 6 is a detail transverse section on line 6—6 of Fig. 3; and

Fig. 7 is a detail transverse section on line 7—7 of Fig. 6.

As shown in Figure 1 the device is mounted upon a railway car 10 having wheels 11, one pair of which is arranged to be driven through bevel gears 12, vertical shaft 13, bevel gear 14, which latter coacts with shiftable bevel gears 15, 16 under control of a sliding collar 17 by manipulation of which the car may be driven in either direction or the gears may be both thrown out of mesh to allow the car to remain stationary while the plant is operative.

To excavate and elevate ballast preferably from a point just outside of the ends of the railway tracks, there is shown an excavating and elevating bucket conveyor 18 mounted upon a frame 19 pivotally supported upon an axis 20 adjacent the center of its length upon a movable platform 21. The platform 21 is shown as mounted upon

wheels or rollers 22 which travel upon tracks 23, only one of which is shown in the drawings, which tracks extend transversely of the railway car 10.

To secure transverse adjustment of the platform 21, there is shown a rack bar 24 fastened upon the floor of the car cooperating with a pinion 25 mounted upon a vertical shaft 26 driven by means of reversible pawl 27 through a hand lever 28.

To adjust the excavating end of the conveyor, the same is shown as supported by a bail 29 hanging from a link 30 carried by a block 31 having a screwthreaded opening engaging a screw 32 operable by a windlass head 33. By revolution of the head 33, the bucket may be adjusted for depth of cut or may be raised to an inoperative position for the purpose of retracting the conveyor 19 into a recess 34 in an edge of the floor of the car by means of movement of the platform 21. The width of the excavator 19 and the depth of the recess 34 are preferably such that when the excavator is retracted into the recess its outer portion will not project beyond the usual outline of the movable railway equipment.

To drive the excavator 19, there is shown diagrammatically a power plant 34 desirably in the form of an internal combustion engine operating to drive through a train of gears 36, 37, 38, and 39, the latter working upon a shaft passing through a sleeve 40 upon which the excavator is pivotally mounted to drive a sprocket wheel 41, which latter through chain 42 drives one of the rollers about which the excavator travels, preferably the upper, through sprocket 43, as shown.

By this arrangement it will be seen that the axis of the shaft driving the sprocket 41 is coaxial with the sleeve 40 upon which the excavator is pivoted.

The elevating conveyor is shown as delivering to a chute 44 leading to a screen 45 mounted for shaking movement as upon rollers 46, the ballast which does not pass through the screen 45 falling to a chute 47 delivering at 48 to be returned to the track.

It will be obvious that in operation the mechanism shown in Figure 1 will be traveling toward the left of said figure.

To cause shaking movement of screen 45, link 49 is shown connecting to the frame of the screen and to a pin 50 carried by a disk 51 mounted upon a shaft 52 supported in bearings 53, 54 fixedly mounted upon the floor of the car 10. 55

To drive the shaft 52 there is shown a pulley 55 feathered upon the shaft 52 and caused to slide upon the shaft with movement of the platform 21 by means of the posts 56, 57 each having 5 a projecting portion 58 adapted to partially surround the shaft to take the pull of the belt 59 and to preserve the alignment of the pulley 55 with the pulley 60 mounted upon shaft 61 driven by gear 38 from the power plant 35.

10 To drive the shaft 62 operating the gears 15 and 16, there is shown a pulley 63 driven by a belt 64 from pulley 65 on shaft 62 and driving the shaft 62 through a transverse shaft 66 and worm and wheel gearing 67.

15 The sleeve 17 may be manually controlled through a link 68 by connections, not shown, extending to the operative positions adjacent or upon the platform 21.

20 To receive the dirt passing through the screen 45, there is shown below the said screen a hopper 69 delivering to a screw conveyor 70 which, as shown in Figure 4, passes transversely and is upwardly inclined to deliver to a second screw conveyor 71, which latter screw conveyor elevates the dirt received from the conveyor 70 and delivers 25 the same to hopper 72 preferably mounted upon an adjacent car coupled in use to the car 10.

25 The hopper 72 is shown delivering to a third screw conveyor 73 extending lengthwise of said coupling car, which latter is indicated at 74 and only a fraction of which is shown in Figure 4.

30 The trough of the screw conveyor 73 is as shown in Figure 7 formed with a central slot at 75 extending longitudinally of the bottom thereof. Desirably a plate 76 closes the slot for a distance 35 beyond the hopper 72. By virtue of the slot 75, the dirt from the conveyor will all escape at first adjacent the front end of the car 74. As the pile 40 of dirt reaches the wall of the conveyor it will automatically form a closure for the slot causing the dirt to be delivered further along the trough until the whole car is filled.

35 To drive the said conveyor 73 there is shown a supplemental power plant 77 operating through shaft 78, Figure 3, and reducing gears 79, to drive bevel gear 80 and shaft 81 of the conveyor 70.

40 To drive the conveyor 71 there is shown a pulley 82 mounted upon shaft 83 driven by bevel gear 80 acting through a belt 84, to drive pulley 85 upon a stub shaft and bevel gears 86, 87, to drive the shaft of the conveyor 71. Upon the last named shaft is mounted gear 88 meshing with the gear 89 upon a shaft 90 extending parallel 55 with conveyor 71, as shown in Figure 4, and operating through universal joints 91, 92, to drive the shaft of the conveyor 73.

45 In operation the apparatus may be conveyed by a usual locomotive, if desired, to the field of work 60 with conveyor 19 in retracted and elevated position. The excavator may be lowered and platform 21 moved transversely so that the excavator nicely clears the ends of the ties whereupon the ballast may be cleaned and returned to the right 65 of way, the dirt thus removed being automatically loaded upon the receiving car. Attendants may rake ballast from between the ties into the path of the conveyor as the car is moved upon the track from the power plant 35.

70 When the right of way must be cleared, the apparatus may be driven through its own power upon a siding or the latter may be done when it is desired to empty the car 74 which is desirably in the form of a dump car.

75 Minor changes may be made in the physical

embodiment of the invention within the scope of the appended claims without departing from the spirit thereof.

I claim:

1. Railway ballast cleaning apparatus comprising, in combination; a railway car; a platform mounted on said car for movement transversely thereof; a power plant carried by said platform; an excavating and elevating conveyor pivotally mounted adjacent its central portion on said platform; drive means for said conveyor actuated by said power plant and operated coaxially of said pivot; a transverse shaft mounted in bearings fixed on said car; means to drive said shaft from said power plant, a pulley feathered and slidably 15 on said shaft; a shaking screen mounted on said car to receive excavated ballast to be cleaned from said conveyor; and means to actuate said screen from said shaft.

2. The combination of claim 1 with gear means 20 to propel said car actuated from said shaft.

3. Railway ballast cleaning apparatus comprising, in combination; a railway car comprising a floor having an edge recess; a transversely movable platform carried by said floor; an excavating 25 and elevating conveyor mounted on said platform, retractible into said recess and projectable therefrom to clear the ends of ties, by movement of said platform; power means carried by said platform to drive said conveyor; shaking screen ballast 30 cleaning apparatus mounted on said car floor; and drive means for said screen actuated from said power means.

4. Railway ballast cleaning apparatus comprising, in combination; a railway car comprising a 35 floor having an edge recess; a transversely movable platform carried by said floor; an excavating and elevating conveyor mounted on said platform, retractible into said recess and projectable therefrom to clear the ends of ties, by movement of 40 said platform; power means carried by said platform to drive said conveyor; shaking screen ballast 45 cleaning apparatus mounted on said car floor; means to deliver clean ballast to the right of way; drive means for said screen actuated from said power means and means actuated from said power means to deliver material passing through said screen to an adjacent car.

5. A ballast cleaning apparatus comprising, in combination; a railway flat car; transverse tracks 50 mounted on the floor of said car; a wheeled platform movable on said tracks; a shaft mounted in bearings carried by said wheeled platform extending transversely of the car; a second shaft 55 parallel with the first named shaft mounted in bearings carried by the car; a power plant mounted on said platform geared to drive said first named shaft; a bucket excavator and elevator geared to be driven by the first named shaft; a shaking screen apparatus driven by said second 60 named shaft and a belt pulley feathered and slidably on the second named shaft driven from the first named shaft; said excavator-elevator delivering to said shaking screen.

6. A ballast cleaning apparatus comprising, in combination; a railway flat car; transverse tracks mounted on the floor of said car; a wheeled platform 65 movable on said tracks; a shaft mounted in bearings carried by said wheeled platform extending transversely of the car; a second shaft parallel with the first named shaft mounted in bearings carried by the car; a power plant mounted on said platform geared to drive said first named shaft; a stub shaft mounted in bearings on said platform 70 geared to be driven by the first named 75

shaft; a bucket excavator and elevator mounted adjacent its central portion to pivot about said stub shaft; chain and sprocket means to drive said excavator from said stub shaft; and manually operated means to adjust said excavator about its pivot.

5. A ballast cleaning apparatus comprising, in combination; a railway flat car; tracks carried thereby transversely thereof, a wheeled platform mounted to travel on said tracks; manually operated means to cause movement of said platform; a power plant mounted on said platform; a shaft mounted in bearings carried by said platform extending transversely of said car geared to be

driven by said power plant; a second transverse shaft parallel with the first named shaft mounted in bearings carried by the flat car; a belt pulley feathered and slideable on said second named shaft driven from the first named shaft; a crank driven by the second named shaft; a shaking screen apparatus driven by said crank; a bucket elevator and excavator mounted on said platform and movable therewith geared to be driven by the first named shaft; said elevator delivering to said 10 shaking screen; and means to deliver cleaned ballast passing over said screen to the right-of-way in place of foul ballast excavated therefrom.

CHARLES A. GILL.
